FLUE CLEANOUT DOOR ASSEMBLY

Kenneth F. Triggs, Huntington, Ind., assignor to The Majestic Company, Inc., Huntington, Ind., a corporation

Application July 12, 1957, Serial No. 671,661

4 Claims. (Cl. 189—46)

This invention relates generally to flue cleanout door assemblies and, in particular, to an assembly of this type in which the door and the door frame are formed of sheet metal.

The advantages of economy and ease of manufacture gained by forming flue cleanout doors and their accompanying door frames of sheet metal are well known. In fabricating these assemblies it has become conventional to form the components for the door hinges from sections stamped from the frame and door blanks. This type of hinge, while lending itself to mass production, has had the disadvantage that the pivotal mounting for the door on the frame is relatively loose, permitting considerable lateral movement of the door relative to the frame.

The primary object of the present invention is to provide a flue cleanout door assembly having a hinge connection comparable in performance to the conventional, more costly, pin and eye door hinge construction.

A further object of the present invention is to provide a flue cleanout door assembly of the type referred to above in which the hinge components are provided by stamping and forming sections of the sheet metal door and frame blanks.

The full nature of the invention will be understood from the accompanying drawings and the following description and claims:

Fig. 1 represents a front view of an assembly embodying the present invention.

Fig. 2 is an enlarged, perspective view of a detail of the hinge construction.

Fig. 3 is a fragmentary, sectional view taken generally along the line 3—3 of Fig. 1.

Fig. 4 is a sectional view taken generally along the line 4—4 of Fig. 1.

Referring initially to Figs. 1 and 4, the flue cleanout door assembly comprises a rectangular sheet metal door frame 10 having rearwardly flanged outer margins and an indented inner marginal area 11. Flanges 12 are formed integrally with the door frame and extend rearwardly therefrom.

Spaced tongues are struck from the flange extending from one side of the frame and, as may best be seen in Fig. 3, are formed to provide circular hinge eyes 13 and 14 having a longitudinal axis positioned forwardly of the plane of the indented area bounding the inner margin of the door frame.

A sheet metal door 16 is adapted to close the opening bounded by the door frame, the door being sized to fit within the indented marginal area 11. Adjacent the hinge eye 14 a generally T-shaped slot 17 is formed in the door and the oppositely extending tongues 18 and 19 thereby provided are accommodated within the hinge eye.

The extremities 21 and 22 of the tongues are bent at right angles to the longitudinal axis of the hinge eye and have curved margins which correspond generally to the curvature of the hinge eye's inner surface. A T-

2

shaped slot 23, identical to the slot 17, is formed in the door adjacent the hinge eye 13, the oppositely extending tongues thereby formed having a configuration identical to that of tongues 18 and 19 and extending within the hinge eye.

A latch 26 is pivotally carried by the door adjacent its free edge and cooperates with a tab 27 struck from the adjacent portion of the door frame for locking the door in closed position.

When assembled, it will be evident that the door is supported on the hinge eyes and, as may best be seen in Fig. 3, the curved margins of the tongue extremities are positioned adjacent the inner surface of the hinge eyes as the door is pivotally moved relative to the frame.

This positioning of the tongue extremities within the hinge eyes as the door is moved provides a stabilization of the door on the frame which is similar to that achieved by use of the conventional cylindrical pin and eye hinge. The stabilized hinge construction thus provided is obtained by stamping and forming sheet metal door and frame blanks, this form of construction having the advantages of economy and ease of manufacture previously referred to.

While the invention has been illustrated and described in detail in the drawings and foregoing description, the same is to be considered as illustrative and not restrictive in character, it being understood that only the preferred embodiment has been shown and described and that all changes and modifications that come within the spirit of the invention and the scope of the claims are also desired to be protected.

The invention claimed is:

1. A flue cleanout door assembly comprising a sheet metal door frame having an indented marginal area defining a rectangular opening, flanges formed integrally with said frame and extending rearwardly from the inner margins thereof, spaced tongues struck from one of said flanges and formed to provide semicircular hinge eyes having their longitudinal axes positioned forwardly of the plane of said marginal area, a sheet metal door adapted to close the rectangular opening, a generally T-shaped slot formed in said door adjacent each of said hinge eyes, the opposed elongated tongues thereby formed at each slot being accommodated within their adjacent hinge eye and having their extremities bent into a plane normal to the longitudinal axis of the hinge eye, said extremities having curved margins corresponding to the curvature of said hinge eyes to limit lateral movement of the door relative to said frame as the door is pivotally moved on the frame.

2. A flue cleanout door assembly comprising a sheet metal door frame defining a rectangular opening, spaced tongues struck from said frame along one of its sides and formed to provide semicircular hinge eyes, a sheet metal door adapted to close the rectangular opening, a generally T-shaped slot formed in said door adjacent each of said hinge eyes, the opposed elongated tongues thereby formed at each slot being accommodated within their adjacent hinge eye and having their extremities bent into a plane normal to the longitudinal axis of the hinge eye, said extremities having curved margins corresponding to the curvature of said hinge eyes to limit lateral movement of the door relative to said frame as the door is pivotally moved on the frame.

3. A flue cleanout door assembly comprising a sheet metal door frame having an indented marginal area defining a rectangular opening, flanges formed integrally with said frame and extending rearwardly from the inner margins thereof, two spaced tongues struck from one of said flanges and formed to provide semicircular hinge eyes having their longitudinal axes positioned forwardly of the plane of said marginal area, a sheet metal door

70

adapted to close the rectangular opening, a generally T-shaped slot formed in said door adjacent each of said hinge eyes, the opposed elongated tongues thereby formed at each slot being accommodated within their adjacent hinge eye, a member carried by each of said elongated tongues and extending in a plane normal to the longitudinal axis of the hinge eye, said members having curved margins corresponding to the curvature of said hinge eyes to limit lateral movement of the door relative to said frame as the door is pivotally moved on the frame.

4. A flue cleanout door assembly comprising a door frame having an indented marginal area defining a rectangular opening, semicircular hinge eyes formed along one side of said frame having their longitudinal axes posi-

tioned forwardly of the plane of said marginal area, a door adapted to close the rectangular opening, a generally T-shaped slot formed in said door adjacent each of said hinge eyes, the opposed elongated tongues thereby formed at each slot being accommodated within their adjacent hinge eye and having their extremities bent into a plane normal to the longitudinal axis of the hinge eye, said extremities having curved margins corresponding to the curvature of said hinge eyes to limit lateral movement of the door relative to said frame as the door is pivotally moved on the frame.
